UNITED STATES PATENT OFFICE.

CHARLES E. GODLEY, OF DETROIT, MICHIGAN, ASSIGNEE, BY MESNE ASSIGNMENTS,
TO C. M. HALL LAMP COMPANY, A CORPORATION OF MICHIGAN.

HEADLIGHT CONSTRUCTION.

Application filed November 21, 1924. Serial No. 751,255.

My invention relates to automobile headlights and more particularly to a mechanical construction and an arrangement of parts designed for effectively employing the principles of the headlight disclosed in my copending application No. 745,301, filed October 23, 1924, on an automobile headlight. In my said copending application, I have illustrated and described a headlamp in which the source of light is disposed in one end of an ovoid reflector which has a partly ribbed concentrating lens mounted in its other end, this reflector having separate portions thereof respectively formed for redirecting light from the said source through differently located foci including a focus at the inner focus of the lens. I have also in my said application disclosed a color filter disposed in conjunctive relation to certain portions of the reflector and to the lens.

My present invention relates to the structural arrangements for facilitating the manufacture, assembly and mounting of the parts of such a lamp; for effectively protecting the reflector and other parts of the lamp against injury from mechanical shocks; for safely housing the needed means for focusing the source of light, and for affording ready access to this focusing arrangement whenever an adjustment is needed. It also provides a reflector construction for such a lamp which will readily permit the composite reflector to be manufactured in a small number of parts and desirably in only two parts; which will insure an accurate alinement of the separately manufactured reflector parts; which will permit the assembled reflector portions to be supported merely from their ends, and which will insure a proper alinement of the reflector with the lens of the lamp.

Furthermore, my invention provides simple means upon the housing for such a lamp for supporting the lens and the forward end of the reflector; and provides simple means for supporting the rear end of the reflector, desirably in an arrangement which will yieldingly urge the entire reflector member forwardly within the housing.

In a still further aspect, my invention provides a lamp body adapted to house a reflector of the above described characteristics and having one section of the body removable for affording access to the interior of this lamp body, provides such a sectional body arrangement in a form in which the remov-

ing of the detachable section will not disturb any of the operative parts of the lamp proper; provides an effective lock for normally securing the detachable body section in its attached position, and desirably arranges this lock so that it can readily be locked or unlocked by means of an ordinary coin. It also provides the body sections with interengaging formations for holding them properly alined, and arranges these formations so as to deter a manipulation of the detachable body section which might cause this section to engage and damage the reflector. Moreover, my invention provides a lamp body for such a purpose which will require a relatively small amount of machining, which will afford a watertight housing for the lamp proper, and which will be handsome in appearance.

In an additional aspect, my invention provides a convenient and firm mounting for the color filter of the lamp, and for this purpose provides a filter holder which reinforces the outer edge of the color filter and suitable space between sections of the reflector for housing such a holder.

Furthermore, my invention provides novel means for securing such a lamp body or casting to a support.

Still further and also more detailed objects will appear from the following specification and from the accompanying drawings, in which—

Fig. 1 is a side elevation of an automobile headlight embodying my invention.

Fig. 2 is an enlarged central and longitudinal section through the same.

Fig. 3 is a transverse section taken along the line 3—3 of Fig. 2 but drawn on a smaller scale and with a part of the rim of the rear reflector broken away to show the clamping rim on the color filter.

Fig. 4 is a central and longitudinal section through the lamp body and lens showing the detachable body portion tilted to the extent of its initial movement thereof during the detaching of this part.

Fig. 5 is an enlarged fragmentary section through adjacent parts of the upper and lower body portions, showing the arrangement of the interlocking formations on these parts.

Fig. 6 is a fragmentary rear view of the lamp, taken from the left hand of Fig. 2 and showing a portion of the lock which

normally holds the detachable body portion in rigidly attached position.

Fig. 7 is a central and longitudinal section through the rear end of the detachable body portion and of the lock carried by this portion, showing the position of the lock when it is unlatched to permit the free movement of the detachable body member.

Fig. 8 is a view taken from the line 8--8 of Fig. 2 to show the inner part of the lock and the adjacent portion of the spring which normally holds the rear reflector member in position.

Figs. 9 and 10 are respectively a side and a front view of the rim for the color filter.

In the embodiment of the drawings, I am showing a headlight including a reflector and lens arrangement for employing the optical features disclosed in my said copending application #745,301. For this purpose, the illustrated headlight includes a substantially ovoid reflector constructed of two parts joined at their larger diameters. One of these parts is a rear reflector member 1 having at its rear end an aperture through which a lamp socket 52 extends in substantially axial alignment with the reflector for supporting an incandescent lamp 3, and having at its forward end a radial flange 4 surrounded by an annular rim 5. This rim 5 is telescoped into a rim 6 formed at the outer edge of a substantially radial flange 7 upon the forward reflector member 2. The reflector member 2 has an opening in its forward end and has its extreme forward end formed into an inwardly directed flange 8 which serves in the manner hereafter described for holding the lens 9 against a flange on a lens ring 10.

To support these parts in properly related position, I provide the forward reflector member 2 rearwardly of the said forward end flange 8 with a radial flange 11 and I secure this reflector member to the lens ring 11 by screws 12 spaced circumferentially of the lens ring. This lens ring itself is attached to the lower part 13 of an ovoid body which is split longitudinally and desirably substantially along a horizontal plane axially of the lamp so as to be composed of two parts 13 and 14. The lower part 13 is desirably stationary, being secured to an adjacent support by convenient means and preferably by a novel type of lamp-supporting clamp hereafter described. This lower body part 13 has the lens ring continuously fastened to it by means of screws 15 which extend through an inwardly directed semi-annular and radial flange 16 and which screws are spaced circumferentially of the said flange. With the lens ring thus initially secured to the lower body member and with the forward reflector member 2 then attached to the lens ring by screws 12, and clamping the lens between this reflector and

the lens, the forward reflector member is held in rigid position with respect to the lens and the lamp body, thus presenting the flange 6 at its rear end in a fixed position in which this flange can readily serve as a guide for the corresponding flange 5 on the rear reflector member 1. Hence this rear reflector member can readily be placed in its proper position by merely sliding it forwardly to telescope its flange 5 into the said flange 6 as shown in Fig. 2.

To hold the rear reflector member in position when thus aligned with the forward reflector member by the telescopic interfitting of the said flanges, I interpose supporting means between the rear end of the reflector and the rear of the ovoid lamp body, desirably in the form of spring means which will compensate for any variations in the thickness of a packing ring 17 disposed between radial flanges on the two reflector members and for permitting the ready detaching and reattaching of the rear reflector member. For this purpose I am here showing a spring 18 which has its forward end clamped between the rear end of the reflector member 1 and the housing 19 of a focusing mechanism associated with the lamp socket 52, and which spring has its rear end abutting against the rear end of the lower body member 13. By making this spring effectively U-shaped in longitudinal section, I can readily permit it to be flexed manually so as to release the rear end of the spring from the lower body member while leaving the forward end of the spring continuously clamped to the rear reflector member 1 by the said shell of the focusing mechanism. In planning such an arrangement, I preferably leave ample room between the rear end of the reflector and the rear end of the lamp body or housing to permit access to the screw 51 of the focusing mechanism, and also to allow room for a slack wire 22 which connects the terminals of the lamp socket 52 to the terminals of a current supply plug 23 which extends through the lower part of the lamp body.

With the parts thus arranged, it will be obvious from Fig. 2 that if the upper body member 14 is removed, a manual compression of the spring 18 will permit the rear reflector member, together with the lamp socket, focusing mechanism, the lamp bulb and the spring 18 to be drawn bodily out of the housing of the lamp. By so doing, I secure free access to the color filter hereafter described, to the forward reflector member and to the inner face of the lens, so as to clean these parts if necessary and also to replace the lamp bulb.

To insure an accurate alining of the two body or casing parts 13 and 14, I provide these parts with relatively interengaging lug and recess formations disposed along the

adjoining edges of these two parts, such as lugs 21 alternating with correspondingly shaped recesses 20, as shown in Fig. 5. These lugs and recesses preferably extend 5 along the interior of each part only for part of the thickness of each part, so as to leave the uninterrupted and flat adjoining portions along the exterior of the lamp body, thereby affording an inconspicuous joint in the 10 closed lamp body.

Since the two body or casing parts must be relatively tilted (as shown in Fig. 4) to permit the lugs 21 to clear the recesses 20, before the contracted forward end of the 15 separable part 14 can be withdrawn from the bore of the lens ring, care would have to be exercised to avoid having the forward end of the detachable body part engage the forward reflector section as such an engagement 20 might easily dent a reflector section formed of thin metal. To obviate the need of such special care, I provide means for limiting the initial tilting of the detachable body part 14, as by providing this part near its 25 forward end with a lug 34 which has limited clearance in the corresponding recess 35 in the stationary part 13. Thus equipped, this lug 34 engages an end wall of the recess 35 to limit the initial tilting of the detachable 30 body part 14 (as shown in Fig. 4), whereupon the part 14 can be slid slightly rearwards to draw the flange 16 out of the lens ring, after which the part 14 can be lifted off freely.

To lock the two body parts to each other, I provide latching means which are preferably disposed at the rear end of the body. For this purpose, I am showing the body as having at its rear end an annular groove 40 24 coaxial with the axis of the lamp and extending into both halves of the body. This groove normally houses a forwardly projecting annular flange 25 on a locking disk 26, the said groove and flange being desirably 45 formed with cam surfaces which will cooperate in forcing the two halves of the body toward each other when the disk 26 is moved forwardly so as to force the flange 25 into the groove 24. To effect such a forcing movement, I provide a screw 27 extending 50 through the disk 26 and threaded through a supporting plate 28 which is loosely supported by screws 29 threaded into the detachable body part 14 from the interior of 55 the latter, as shown in Figs. 7 and 8. Then I provide means, such as a grip ring 31, for limiting the unscrewing movement of the screw 27, and interpose a compression spring 30 between the locking disk 26 and 60 the supporting plate 28.

When the screw 27 is tightened, the compression of the spring 30 between the parts connected by this screw prevents the screw 65 from being loosened by jarring and hence keeps the locking disk 26 in its latching

position. On loosening the screw by means of a screwdriver (or of a coin, which can easily be used as a substitute) the expansion of the spring slides the disk 26 rearwardly in Fig. 7, thereby unlocking the latch. As 70 here shown, the lower end of the supporting plate 28 is formed so as to fit into the forked rear end of the flat spring 18, so that this plate 28 also serves to center the outer end of the spring. 75

To support the color filter, which is here shown as comprising a semi-circular glass plate 36 provided at its diametric upper edge with a notch 37, I desirably mount this in a metal rim 38 which reinforces the outer edge of the glass and which affords means for rigidly securing the color filter in its proper operative position. This rim 38 has its major portion of a channel section tightly straddling the curved edge of the glass color filter, one side of the channel being bent over the straight edge of the glass at the opposite ends of the said curved edge, so as to anchor the glass against rotation about the axis of the curved rim. Then I provide this rim 80 with perforations, such as the screw holes 56 at the projecting upper ends of the rim and the notch 37 in the bottom or medial portion of the rim, for receiving screws 58 whereby this rim is screwed to the rear 85 face of the outwardly directed flange which connects the rear end of the forward reflector section 2 with the cylindrical annular flange 6, all as shown in Figs. 2, 9 and 10. I also desirably provide a spring 61, 90 secured to the bottom of the forward reflector section as shown in Fig. 2, entering a bottom notch in the color filter and continuously pressing the color filter upwardly 95 into engagement with the rim portions 100 which overhang the diametric upper edge of the color filter.

However, while I have illustrated and described various novel features of my lamp in a construction embodying certain highly 110 desirable details of construction and arrangement, I do not wish to be limited to what is thus shown. Obviously, many changes might be made without departing either from the spirit of my invention or 115 from the appended claims.

I claim as my invention:

1. In a lamp, a housing having an opening in its front, a reflector disposed within the housing and engaging the said front, the rear end of the reflector being spaced from the back of the housing; a focusing socket mounted on the rear end of the reflector; and a compression spring interposed between the said rear end and the back of 120 the housing for forcing the reflector against the said front, the said spring having its forward end secured to the reflector and having its rear end in releasable engagement with the back of the housing, the intermedi- 125

ate portion of the spring extending at one side of the focusing socket to permit access to the latter.

2. In a lamp, a hollow body having an aperture at its forward end, an ovoid reflector disposed therein and comprising interfitting front and rear sections, the front section having an aperture at its forward end, means on the body for supporting the front section with the said apertures in alinement, and yielding means interposed between the body and the rear reflector section for supporting the rear end of the reflector and for holding the said sections in interfitting relation, the said interfitting being releasable by a compressing of the yielding means to permit a separation of the reflector sections.

3. In a lamp, an ovoid reflector apertured at its forward end and having two sections adjoined substantially at the greatest transverse diameter of the reflector, the said sections having relatively interfitting portions at their adjoined ends for holding them in alinement, a body housing the reflector and having the forward reflector section secured to its front, and a compression spring interposed between the rear ends of the reflector and the body and secured to only one thereof, the interfitting of the reflector sections being so limited as to permit a release thereof by a rearward movement of the rear reflector section against the pressure of the spring, thereby permitting the rear reflector section to be detached from the forward section.

4. In a headlight, a reflector having at its mouth an opening bordered by a radial flange, a body housing the reflector and having at its mouth an opening bordered by a flange, a lens ring sleeved within the flange, screws extending through the flange on the body from the interior of the latter into the lens ring for securing the reflector to the body, the body being split longitudinally to afford access to the said screws, and means accessible from within the reflector for securing the reflector to the lens ring.

5. A lamp body split along a longitudinal medial plane and having an opening at one end, a lens ring alining with the opening in the body and secured to one part of the body only, a reflector having its forward portion inserted through the said opening from the rear thereof and having its forward end secured to the lens ring, and means for detachably securing the other part of the body to the aforesaid part.

6. A lamp body split along a longitudinal medial plane and having an opening in one end, a lens ring alining with the opening in the body and secured to one part of the body only, a reflector secured to the lens ring, and means for detachably securing the other part of the body to the aforesaid part; the said means comprising relatively interfitting for-

mations on the lens ring and the said other body part, and releasable means at the rear end of the body for securing the body parts to each other.

7. A sectional lamp body comprising a stationary section and a detachable section, a reflector disposed within the body and comprising two sections disposed behind each other, attaching means for securing one reflector section to the stationary body section, and means for detachably holding the reflector sections in their normal cooperative relation, both of the said means having access thereto afforded by the removing of the detachable body section.

8. The combination with a reflector, of a housing having its main portion split longitudinally of the reflector to afford a detachable body part, the detachable body part and other parts of the housing having interengaging formations for preventing movement of the said detachable part in any direction along the plane of the split when the body parts are in their relative normal dispositions, certain of the said interengaging formations permitting the detachable part to be tilted to release others of the said formations; and coacting means on the body parts for limiting the extent of such tilting.

9. A lamp construction as per claim 7, in which the two body portions are provided at their adjoined edges with interfitting formations for preventing relative movement of the said parts in the said plane.

10. A lamp body split longitudinally to divide it into two parts, the said parts having integral interengaging formations preventing relative movement thereof laterally of their juncture while permitting relative longitudinal movement thereof, means at one end of the body for holding the parts adjoined at said end, and clamping means disposed at the other end of the body and releasable from outside the body for securing the parts to each other at the last named end, both of the said means being mounted on one of the said parts and arranged to permit the detaching of the other part without detaching the said means from the part on which they are mounted.

11. A lamp body construction as per claim 10, in which the clamping means comprise a pair of members respectively engaging opposed inner and outer surface portions of the body at the said other end thereof, one of the members being secured to one part of the body and the other member having formations normally interlocking with both parts of the body, and a screw connecting the said two members.

12. A lamp body construction as per claim 10, in which the clamping means comprise a pair of members respectively engaging opposed inner and outer surface portions of

the body at the said other end thereof, one of the members being secured to one part of the body and the other member having formations normally interlocking with both 5 parts of the body, a screw connecting the said two members, and a compression spring interposed between the said members for separating them upon a loosening of the screw so as to release the interlocking of the 10 said formations with one part of the body.

13. A lamp body construction as per claim 10, in which the two body parts have adjoined semi-circular grooves at the said end of the body, and in which the clamping 15 means comprise a washer having a flange

normally seated in the said grooves and a screw for drawing the washer towards the said end to hold the flange in the grooves.

14. In a lamp, a reflector comprising two sections adjoined in continuation of each other, a filter holding rim fastened to one section at the end thereof which adjoins the other section, and a color filter mounted in the said rim, the said rim having a U-shaped portion extending along and straddling the 25 outer edge of the color filter.

Signed at Detroit, Michigan, November 19th, 1924.

CHARLES E. GODLEY.
